UNITED STATES PATENT OFFICE.

LUDWIG SPACHTHOLZ AND JOSEPH WINGERSON, OF KITTANNING, PENNSYLVANIA.

APPARATUS FOR GRINDING PLATE-GLASS.

No. 916,935.

Specification of Letters Patent.

Patented March 30, 1909.

Original application filed December 14, 1907, Serial No. 406,450. Divided and this application filed February 25, 1908. Serial No. 417,766.

To all whom it may concern:

Be it known that we, LUDWIG SPACHTHOLZ and JOSEPH WINGERSON, residents of Kittanning, in the county of Armstrong and State of Pennsylvania, have invented certain new and useful Improvements in Apparatus for Grinding Plate-Glass, of which the following is a specification.

This application is a division of our application filed December 14, 1907, Serial No. 406,450, relating to grinding plate glass, and has particular reference to the apparatus therein disclosed.

One object is to provide mechanism for grinding several relatively small plates while grinding a large plate or field. By preference, the area of each of the smaller plates is a fraction of the area of the large plate—say approximately one-fourth, so that by applying two of the smaller plates at one time to the surface of the large plate, those two plates may be ground while grinding the face of the large plate.

As further characteristic of the invention, a certain number of small plates are rough-ground while rough-grinding the large plate, and then the same small plates are smooth-ground while similarly grinding the large plate. Thus, if the area ratio is 4 to 1, two of the small plates are applied to the large plate and by the time they are completely rough-ground about one-half of the process of rough-grinding the large plate has been accomplished. The two small plates are then removed and two other unground plates substituted, and by the time the substituted plates have been fully rough-ground, the rough-grinding of the large plate has been completed. The smooth grinding of the plates may then proceed without removing the last applied small plates until they have been smooth-ground and are ready for the final polishing. When this has been accomplished, the process of smooth-grinding the large plates has proceeded about one-half toward completion. The small plates that were first rough-ground are then substituted for the smooth-ground plates, and by the time the smooth-grinding of these substituted plates has been accomplished the smooth-grinding of the large plate has been completed. By thus grinding one plate upon another, practically double the area is ground as compared with the old practice of grinding a single surface by means of iron or other

runner or grinding devices. In addition to increasing the output, the expense of maintaining the runner faces is wholly eliminated, and as such runners wear quite rapidly the cost of keeping them in working condition is considerable.

In practicing the invention, it is immaterial whether the runners are positively driven, or propelled solely by their engagement with the large plate ordinarily carried by a rotating table.

Apparatus embodying the improved devices is illustrated in the accompanying drawings, Figure 1 being a side elevation thereof, partly in section, one of the plate holders being shown raised. Fig. 2 is a top plan view of the table and plate holders, one of the latter showing a clamping mechanism while only the top surface of the other detachable plate holder head is shown. Fig. 3 is a vertical sectional view on a larger scale of one of the holders. Figs. 4 and 5 are detail views of the clamping device. Fig. 6 illustrates a modification of the operating gearing.

Referring to the drawings, 2 designates the large rotating table supported on the central shaft or axle 3, the table and its rotating means being of the usual well known construction.

4 designates a frame above the table, and in the embodiment here illustrated two vertical shafts 5 are journaled therein, eccentric to shaft 3 and at equal distances therefrom, each carrying at its lower end the four horizontally radiating arms 6.

7 designates the plate holder heads. By preference each head is formed of cast iron, with its upper surface reinforced by circular flange 8 and the four ribs 9 radiating from the center to the flange. The top faces of these ribs are flat like the under surfaces of arms 6 which register therewith and bear thereon when the head is in position. For securing the head, two clamping devices are preferably employed at opposite sides of the center, the same being carried by two of the arms 6. Each device consists of an inverted U-shaped yoke member 10 having its opposite arms slotted vertically at 11 to move on the transverse pins 12 in arm 6. The lower extremities of the yoke-arms are formed with hooks 13 to engage pins or lugs 14 projecting from opposite sides of ribs 9. The threaded stem 15, operating through the upper end of the yoke by means of hand wheel 15', raises

and tightens the clamp with the hooks engaging lugs 14. Two of these clamping devices operate to securely hold the head, and they are of such construction and may be so manipulated that the heads may be quickly and conveniently released. To accurately center the heads and hold them centered, each shaft 5 may be projected at 16 to enter a corresponding central depression 16' in the head, 10 and a pin or lug 17 may be similarly projected from each of arms 6 to enter a depression 17' in each of ribs 9. The heads are preferably square. For a table thirty feet in diameter each of the two heads may be 12 feet 15 square. By so operating the holders that the corners of one head approach the edges of the other head between its corners, there is no danger of collision, while at the same time their paths of movement so overlap as to effectually 20 operate on the whole area of the table. For thus maintaining the plate holders they may be geared together directly by wheels 18, as in Fig. 2, and thus rotate in the same direction, or by interposing a pinion 19 between 25 gears 18, as in Fig. 6, they may be driven in reverse directions.

In operation, a plate or field of glass 20 is cemented on table 6 in the usual manner, while a plate 21 is similarly centered to the 30 under face of each head 7. With two of the holders in position, the rough-grinding proceeds, sand and water being applied as in the present practice. As here shown the holders are propelled by their contact with the table, 35 but they may be positively driven. No novelty is claimed in this connection.

As the area of glass on the table is much larger than the combined areas of the two smaller plates, being double in the example 40 here given, the rough-grinding of the two small plates 21 is completed by the time the rough-grinding of the large plate 20 is approximately one-half finished. At this stage the machine is stopped, and the two heads 7 carrying the fully rough-ground plates are removed and similar heads with fresh plates 45 are substituted for them. The operation then proceeds, and by the time the substituted plates have been rough-ground, the 50 rough-grinding of large plate 21 has been completed. The plates are then ready for the smooth-grinding process in which a finer abrasive, such as emery, is used. This may proceed at once, the small plates last rough- 55 ground being the first to be smooth-ground, hence those plates are not removed from the machine from the time they are first applied until after the whole grinding operation has been completed and they are ready for 60 polishing. By the time these plates are fully smooth-ground the same process has been approximately one-half completed as to the large plate 21, and is fully completed along with the smooth-grinding of the set of 65 small plates which were first rough-ground.

For connecting and disconnecting heads 7, each of shaft 5 may be raised and lowered in frame 4 by a lever 22. It will be noticed in this connection that the connecting gears are of such width that this vertical movement of the shaft does not disengage them, and hence the positioning of the small-plate 70 holders with relation to each other is always maintained.

It will be understood that what we term 75 the glass plate or field 21 on table 2 is in practice usually made up of a number of plates of various shapes and areas, the purpose being to cover the table as fully as possible. The same is true of the smaller 80 plates. While some plates may be the exact size of heads 7, it more often happens that their surfaces are covered with several plates. Hence, in referring to the small plates and to the large or table plate, we do not necessarily mean a single plate but rather a glass 85 covered surface or field which may be made up of one plate or several, according to circumstances.

The method herein disclosed forms the 90 subject matter of our above mentioned application for Letters Patent.

We claim:—

1. Plate glass grinding apparatus comprising a movable table, a plate of glass secured thereto, movable plate holders of equal size above and smaller than the table, and plates of glass secured to the under faces of the holders for bearing on the large plate 95 secured to the table. 100

2. Plate glass grinding apparatus comprising a rotatable table, a plate of glass secured thereto, two plate holders of equal size above the table and equally spaced from the center thereof with portions of the holders 105 movable successively over said center, and plates of glass secured to the under faces of the holders for bearing on the large plate secured to the table.

3. Plate glass grinding apparatus comprising a rotatable table, a plate of glass secured thereto, two square plate holders of like size rotatably supported above the table in diametrically opposite relation and at equal distances from the table center, the 115 square holders being of such size that the corners thereof successively overlap the table center, and plates of glass secured to the 120 holders for bearing on the plate secured to the table. 125

4. A plate holder for plate glass grinding machines comprising a head, a supporting shaft, arms radiating from the shaft, and means for detachably securing the head to 130 said arms. 125

5. A plate holder for plate glass grinding machines comprising a head, a rotatable supporting shaft, arms radiating from the shaft, and adjustable clamping devices on the arms for detachably engaging the head. 130

6. A plate holder for plate glass grinding machines comprising a head having radially arranged ribs on the upper side thereof, a rotatable supporting shaft, arms radiating from the shaft complementary with and adapted to bear against the ribs of the head, and means for securing together said arms and ribs.

7. A plate holder for plate glass grinding machines comprising a head, radially arranged ribs on the upper side thereof, a rotatable supporting shaft, arms radiating from the shaft complementary with and adapted to bear upon said ribs, pins projecting from the ribs, and yoke-shaped clamps movably secured to the arms and provided with hooks for engaging the pins on said ribs.

8. A plate holder for plate glass grinding

machines comprising a head, ribs on the upper side thereof, pins projecting from the ribs, a rotatable supporting shaft, arms projected from the shaft, yokes embracing the arms and having hook-shaped extremities which engage the pins on the ribs, each yoke being slotted, a pin projected through the slotted yoke and through the arm which the yoke embraces, and a screw adjustable in the yoke and adapted to bear upon the arm.

In testimony whereof we affix our signatures in presence of two witnesses.

LUDWIG SPACHTHOLZ.
JOS. WINGERSON.
